(57) **CLAIM**

I claim the ornamental design for a utility vest, as shown and described.

DESCRIPTION

FIG. 1 is a perspective view of a utility vest, showing my new design;

FIG. 2 is a front elevation view thereof;

FIG. 3 is a rear elevation view thereof;

FIG. 4 is a left-side elevation view thereof;

FIG. 5 is a right-side elevation view thereof;

FIG. 6 is a top plan view thereof; and,

FIG. 7 is a bottom plan view thereof.

The dashed lines showing a person and various tools in FIG. 1 are included for the purpose of illustrating the invention in use, and form no part of the claimed design.

The broken lines on the garment in FIGS. 1 through 7 represent stitching.
